UNITED STATES PATENT OFFICE.

CHARLES E. VERGE, OF DETROIT, MICHIGAN.

DESIGN FOR A CASING FOR FLUSH-TANKS.

SPECIFICATION forming part of Design No. 22,360, dated April 18, 1893.

Application filed November 2, 1892. Serial No. 450,794. Term of patent 7 years.

To all whom it may concern:

Be it known that I, CHARLES E. VERGE, of Detroit, in the county of Wayne and State of Michigan, have invented and produced a new and original Design for a Casing for Flush-Tanks for Water-Closets, of which the following is a specification.

My invention consists in a design for casings for flush tanks for water closets.

Figure 1 is a front elevation, and Fig. 2 is a top plan view.

B represents the metal tank which is made rectangular and this is usually inclosed in a wooden casing also of the same shape.

My design consists in a casing A of the shape shown in Fig. 2, that is having rounded corners C C, a swelled front D, and swelled rear corners E E. The molding F on the top of the casing follows the lines of the casing as shown in dotted lines in Fig. 2.

What I claim as my invention, and desire to secure by Letters Patent, is—

The design for the casing of a flush tank herein shown and described.

CHARLES E. VERGE.
